UNITED STATES PATENT OFFICE.

VALENTINO DE VICARI, OF CHICAGO, ILLINOIS.

PENHOLDER.

1,192,760.

Specification of Letters Patent. Patented July 25, 1916.

Application filed April 27, 1916. Serial No. 93,920.

To all whom it may concern:

Be it known that I, VALENTINO DE VICARI, a subject of the King of Italy, residing at Chicago, in the county of Cook and State of Illinois, have invented certain new and useful Improvements in Penholders, of which the following is a specification.

This invention relates to certain new and useful improvements in pen holders.

10 The primary object of the invention is the provision of a pen retaining device for a holder whereby the writing pen is readily secured to and released from the holder.

15 A further object of the invention is the provision of a writing instrument of substantially the usual form of pen holder, the same being adapted for receiving the writing pen clamped therein, the same being readily released and removed without being 20 grasped by the operator no matter what condition the pen may be in, thus preventing a soiling of the fingers as well as insuring the removal of the pen without breaking the same in such cases for instance, as 25 where the pen is slightly corroded.

The invention therefore contemplates the provision of a handle or holder having a pivoted clamping lever for removably securing a pen in its operative position therein. 30 With these general objects in view and others that will appear as the nature of the invention is better understood, the same consists in the novel construction, combination and arrangement of parts hereinafter more 35 fully described, illustrated in the accompanying drawings, and then claimed.

In the drawings forming a part of this application and in which like designating characters refer to corresponding parts 40 throughout the several views:—Figure 1 is a side elevation of the present device with a pen position therein. Fig. 2 is an enlarged central longitudinal sectional view through the pen holding end portion thereof, the securing lever being shown by dotted lines in its released position. Fig. 3 is an elevational view of the rear side of the same. Fig. 4 is a transverse sectional view taken upon line IV—IV of Fig. 2. Fig. 5 is a 45 perspective view of the lever mounting sleeve removed, and Fig. 6 is a perspective view of the clamping lever detached.

50 It will be first understood that the present device is designed for removably securing a pen of the usual pointed construction such as illustrated at 10 within an axial end

chamber 11 of any form of holder or handle such as the tapered pen holder 12 herein shown. A split sleeve 13 is snugly fitted within the chamber 11 being provided with 50 parallel inturned flanges 14 adjacent its side slot 15 and a clamping or locking lever 16 is pivoted between the flanges 14 by means of a transversely arranged pin 16' projecting through said flanges and lever 65 as well as through opposite perforations 17 in the sides of the sleeve 13.

The lever 16 is substantially segmental in form having its straight edge 18 lying normally flush with the adjacent side of the 70 holder 12 when the pen 10 is in its secured position, it being understood that the pivoted movements of the lever 16 are permitted by the arrangement of a longitudinal side slot 19 in the holder 12 which communicates with the chamber 11 thereof. The curved edge 20 of the lever 12 is provided with a substantially semi-circular cam 21 adapted for engaging the inner face of the pen 10 and clamping the same against the 80 opposite inner surface of the sleeve 13 when the lever is in its substantially longitudinal relation with respect to the handle 12 and with the lever edge 18 in alinement with the adjacent outer surface of the said 85 handle. The forward end of the lever 16 projects outwardly of the open end of the chamber 11 and constitutes a pointed releasing arm 22 whereby the lever may be 90 swung upon its pivot pin 16 for releasing the pen 10 from its clamped engagement by the cam 21.

A ferrule 23 is secured encircling the forward end of the holder 12 being secured thereto by means of a circumferential inwardly-extending bead 24, an inwardly-extending forward flange 25 being arranged upon the ferrule 23 for abutting the forward end of the holder 12 as well as the adjacent end of the sleeve 13, it being noted that the lever 16 is provided with a notch or cut-away portion 26 to accommodate the ferrule 23 at the rear side of the handle 12 lying substantially opposite the pen 10 when positioned in the holder.

From this detailed description of the device, it will be at once apparent that when the lever 16 is in its dotted line position as illustrated in Fig. 2 of the drawing, the pen 10 may be inserted within the sleeve 13 and a pressure of the finger upon the lever edge 18 will swing the lever upon its pivot pin 16'

for firmly engaging the cam 21 against the pen 10 and locking the same in the holder chamber 11 with the writing point of the pen projecting in an operative position outwardly thereof. When desired to remove the pen 10 from the holder 12, the releasing arm 22 is pressed inwardly until the lever 16 assumes its dotted line position illustrated in Fig. 2, and at which time the pen 10 will be entirely released from the cam 21 and the pen may be then readily removed from the holder by either shaking the holder or dislodging the pen by engaging the same with any convenient object, it being noted that it is not necessary for the operator to grasp the pen to remove the same unless so desired. While the slot 19 accommodates the lever 16 extending through the side wall of the chamber 11, it will be seen that a portion of the holder 12 at the rear of the chamber is also slotted, providing a form of seat 27 for receiving the pointed free end of the lever 16 when in its operative position.

While the form of the invention herein shown and described is what is believed to be the preferred embodiment thereof, it is nevertheless to be understood that various forms, modifications and arrangements of the parts may be made without departing from the spirit and scope of the invention as claimed.

What I claim as new is:—

1. A holder for a writing pen comprising a holding member having an axial open ended bore at one end thereof and a side slot communicating with the said bore and extending inwardly at one side of the holder forming a receiving seat, a split sleeve positioned within the said chamber having in-

turned parallel flanges, a segmental lever 40 pivoted to the said sleeve shiftably arranged between the said flanges and through the said slot and having the inner curved end positioned upon the said seat when the lever is in its closed arrangement, the said lever 45 being further provided with an engaging cam for the said pen and with a forwardly projecting pointed releasing arm whereby the pen is released from the holder when the inner end of the lever is positioned outwardly of the said slot and seat.

2. A holder for a writing pen comprising a holding member having an axial open ended bore at one end thereof and a side slot communicating with the said bore and extending inwardly at one side of the holder forming a receiving seat, a split sleeve positioned within the said chamber having in-turned parallel flanges, a segmental lever pivoted to the said sleeve shiftably arranged between the said flanges and through the said slot and having the inner curved end positioned upon the said seat when the lever is in its closed arrangement, the said lever being further provided with an engaging 65 cam for the said pen and with a forwardly projecting pointed releasing arm whereby the pen is released from the holder when the inner end of the lever is positioned outwardly of the said slot and seat, and a securing ferrule upon the forward end of the said holder overlying the adjacent end of the said sleeve, the said lever having a notch in its outer side at a point adjacent the said ferrule.

In testimony whereof I affix my signature.

VALENTINO DE VICARI.
